PATENTED AUG. 15, 1905.

S. I. BUTTERS.

ILLUMINATED SIGN.

APPLICATION FILED JAN. 9, 1905.

WITNESSES:

Alfred T. Sage

The image contains two parts. On the left is a cursive signature that reads "Alfred T. Stage". To the right of the signature is a technical cross-sectional diagram of a mechanical assembly. The diagram shows a central vertical rod with a circular top. A horizontal plate is attached to the top of the rod. A spring is positioned between the rod and the plate. A small circular component is attached to the side of the rod. The base of the assembly is a rectangular housing with internal features. Two labels, "D" and "D'", are placed near the base, pointing to specific parts of the housing.

UNITED STATES PATENT OFFICE.

SAMUEL I. BUTTERS, OF CLARKSBURG, WEST VIRGINIA.

ILLUMINATED SIGN.

No. 797,492.

Specification of Letters Patent.

Patented Aug. 15, 1905.

Application filed January 9, 1905. Serial No. 240,263.

To all whom it may concern:

Be it known that I, SAMUEL I. BUTTERS, a citizen of the United States, residing at Clarksburg, in the county of Harrison, State of West Virginia, have invented certain new and useful Improvements in Illuminated Signs, of which the following is a specification, reference being had therein to the accompanying drawings.

This invention relates to illuminated signs, and particularly to a structure composed of a plurality of sections which may be assembled in varied relations.

The invention has for an object to improve the construction of the sections of an illuminated sign whereby they may be economically produced and operated and an efficient simple structure effected.

A further object of the invention is to provide an improved construction and arrangement of the reflectors for use within an illuminated sign and of the means for conducting an electric current and for supporting an illuminating-lamp within the sign.

Other and further objects and advantages of the invention will be hereinafter set forth and the novel features thereof defined by the appended claims.

In the drawings, Figure 1 is a perspective view of a sign with parts broken away and in section; Fig. 2, a central horizontal section of the parts shown in Fig. 1; Fig. 3, a central vertical section of the connecting ornament for the supporting-rods of the sign; Fig. 4, a detail perspective view of the flange provided at one end of the sign-sections; Fig. 5, a horizontal section through the abutting ends of two sections of the sign; Fig. 6, a plan view of a similar part; Fig. 7, a side elevation of one of the sign-sections with the translucent material removed; Fig. 8, a vertical section through the parts shown in Fig. 7; Fig. 9, a detail horizontal section of a modified arrangement of the reflectors, and Fig. 10 a perspective view of a modified assemblage of the sign-sections.

Like letters of reference refer to like parts in the several figures of the drawings.

The sign herein illustrated is composed of a series of sections, each of substantially similar construction, and embodying a body portion A, bent into any desired configuration, and provided at one or both sides with an opening A' to permit the passage of light outward therefrom. The body may be formed of a single piece open at its bottom and there

provided with inturned flanges A², which are secured to a base-plate A³, provided with an upwardly-extending flange A⁴ at each end spaced from the body A of the sign so as to provide a seat or groove to receive the translucent member B inserted before the opening A' of each section. For the purpose of providing a side groove to retain the translucent plate B in position each of the sign-sections is provided at one end with a laterally-disposed portion A⁵, having at its free end oppositely-disposed flanges A⁶, spaced from the body A of the section. These flanges A⁶ provide a seat to receive the telescoping free end A⁷ of each section. This telescoping end at the upper portion of the sign extends beneath the overlapping portion A⁸ of an adjacent section, which is disposed at the flanged end of the section, as illustrated in Fig. 6. Within each of the sections a bottom brace C is provided, having at opposite sides inclined portions C', each provided beneath the same with conduits for the electric conducting-wires C² for conveying current to the lamps C³ used for illuminating the sign. These lamps may be supported in any desired manner—for instance, by means of brackets C⁴, secured to the bottom plate adjacent to each of the openings A', as shown by dotted lines in Figs. 1 and 7, while the current is conveyed to the lamps from the conductors in the opposite conduits by means of loops C⁵, as shown in Figs. 2 and 8, such wires being passed through a suitable opening in the inclined walls C' of the bottom brace C.

The sign-sections are capable of being supported in various manners, and a desirable form thereof is herein shown as comprising the tubular portion D, secured to the top and bottom of each sign member and adapted to receive the supporting-rod D', Fig. 3, passing through the tubes D and threaded into a corner-piece D², so as to be adjustable thereon.

The sign-sections are each provided with open ends, and when assembled to form the sign the ends of the final sections in each series are closed by means of cover-plates E and E', the former fitting over the free end of the section by means of a flange E² and the latter provided with a flange E³, adapted to fit within flange A⁶ at the free end of the final section. Each of these cover-plates is provided with tubular portions D³, secured thereto and adapted to receive the rods D⁴, by which the parts are supported in position, these rods being adjustably connected to the corner-piece

D^2 by means of the threaded pin D^5 , rotatably mounted in said piece and having a threaded end D^6 entering a socket in the end of the rods D^4 , as shown in Fig. 3. By this means when the sections are assembled they may be drawn into close and tight contact, and thus held by means of the corner connections herein shown or any other desirable form of adjustable connection. When found desirable, any suitable character of ornament, such as shown at D^7 , may be provided upon the cover-plate.

The translucent plates B , which are retained in position by the flanges A^4 and A^6 upon the sections, may be of any desired character or material suitable for permitting the passage therethrough of the light-rays from within the sign and may contain letters or other characters found suitable for the purpose. At opposite sides of each of the lamps C^3 , within the sign, are reflectors B' of curved formation, preferably having their convexed face next the lamp, so that the rays of light are directed within the area of the opening of the frame-section and reflected therethrough. These openings may be provided upon opposite sides of the sections, as shown in Fig. 2, or, if found desirable, the opening A' may be omitted from one wall thereof and a supplemental reflector B^2 disposed at that point, Fig. 9, while, if desired, the reflectors B^3 at each side of the lamp may be disposed with their concaved faces next thereto. It has been found desirable to form this reflecting-surface of a corrugated shape, as well as segmental, thus more evenly distributing the reflecting and light-transmitting power thereof.

The illuminating-lamps for the sign may be disposed at either the top or bottom thereof or in both positions, as shown in Figs. 7 and 8, in which construction the brace and conduits to the lamp are duplicated at the top of the case. Any desired form of light may be used instead of the electric lamp herein shown.

The sign-sections are capable of being assembled in different relations to form a sign reading either vertically or horizontally, and in the former instance the parts may be assembled as shown in Fig. 10, wherein each of the sections may be so disposed within the supporting-rods that the letters or characters therein may be read in a vertical plane. This may be accomplished by the use of end covers E^5 , provided at one of the open ends of each section and having secured thereto tubular sections E^6 , through which the supporting-rods E^7 pass, which rods are connected by the corner-pieces D^2 , as hereinbefore described. The cover E' is used at the opposite end of each section.

The sign is composed of independent sections which are interchangeable in position and character and when assembled within the frames and secured by the rods, as hereinbefore described, are adapted to receive the de-

sired letter-plates, which are illuminated by the lamps disposed within the sign, and these lamps may be readily connected with the conducting-wires disposed in the opposite conduits within the sign-sections. These conduits provide a protection for the electric conductors, by which they are removed from any contact with the atmospheric conditions or from any possibility of short-circuiting by contact with each other. The corrugated segmental reflectors at opposite sides of each lamp concentrate the rays of light so as to most efficiently illuminate the sign-plates inserted within the sections, while the telescoping connections between these sections permit their assemblage in close contact, and the series thereof may be increased or decreased at will by the insertion or removal of sections.

It will be obvious that changes may be made in the details of construction and configuration without departing from the spirit of the invention as defined by the appended claims.

Having described my invention and set forth its merits, what I claim, and desire to secure by Letters Patent, is—

1. A sign comprising a plurality of independent sections constructed and arranged for engaging contact with each other, means for removably supporting sign-plates upon each of said sections, and a supporting-frame connected with the assembled sections.

2. A sign comprising a plurality of independent sections adapted to be disposed in contact with each other, means for removably supporting sign-plates upon each of said sections, a supporting-frame surrounding the assembled sections, and means for adjusting said frame at the points of intersection thereof.

3. A sign comprising a plurality of independent sections adapted to be disposed in contact with each other, means for removably supporting sign-plates upon each of said sections, a supporting-frame surrounding the assembled sections, means for adjusting said frame at the points of intersection thereof, illuminating means within each section of said sign, and reflectors disposed at opposite sides of said illuminating means.

4. A sign-section comprising a body portion having an apertured side wall, illuminating means opposite said aperture, convexed reflectors disposed at the opposite sides of said aperture, and a bottom brace for said section inclined at its opposite sides to provide conduits.

5. A sign-section comprising a body portion having an apertured side wall, illuminating means opposite said aperture, convexed reflectors disposed at the opposite sides of said aperture, a bottom brace for said section inclined at its opposite sides to provide conduits, a flange surrounding the bottom and one side of said aperture, and a sign-plate adapted to be retained by said flange.

6. A sign-section comprising an apertured

body portion, illuminating means disposed therein, a laterally-extending wall at one end of said section provided with a retaining-flange at its free end, and a sign-plate adapted to fit behind said flange.

7. A sign comprising a plurality of sections each provided with tubular members secured to the outer wall thereof, supporting-rods extending through said tubes, and a corner-piece for connecting and adjusting the rods at their points of intersection.

8. A sign comprising a plurality of sections each provided with tubular members secured to the outer wall thereof, supporting-rods extending through said tubes, a corner-piece adjustably threaded upon each of said rods, and pins rotatably mounted in said corner-pieces and adjustably threaded into an intersecting rod.

9. In a sign, a plurality of sections open at their opposite ends and supported in overlapping contact with each other, and cover-plates for the open end of the terminal sections.

10. In a sign, a plurality of sections open at their opposite ends and supported in overlapping contact with each other, cover-plates for the open end of the terminal sections, conduits provided at the opposite sides of each of said sections, an electric conductor extending through said conduits, and an electric lamp supported within each section intermediate of the conduits.

In testimony whereof I affix my signature in presence of two witnesses.

SAMUEL I. BUTTERS.
